(57) **CLAIM**

The ornamental design for a set of aircraft windows, as shown and described.

DESCRIPTION

FIG. 1 is a front right perspective view showing selected set of aircraft windows according to an embodiment of our design; FIG. 2 is a front elevational view thereof, the rear being a mirror image;

FIG. 3 is a left side elevational view thereof, the right side being a mirror image; and,

FIG. 4 is a top plan view thereof, the bottom being a mirror image.

Throughout the Figures, broken lines showing environment or structure are for illustrative purposes only and form no part of the claimed design.
